SPRAY ROLLER DISPENSER

Filed July 5, 1947

FIG. 1

FIG. 2

INVENTOR

Everett A. Johnson

UNITED STATES PATENT OFFICE

2,563,842

SPRAY-ROLLER DISPENSER

Everett A. Johnson, Park Ridge, Ill.

Application July 5, 1947, Serial No. 759,098

4 Claims. (Cl. 91—62.5)

1

This invention relates to an improved spray-roller dispenser and has for a principal object the provision of a portable dispensing apparatus in combination with a liquid reservoir adapted to be used in manipulating the dispenser.

An additional object is to provide a novel and improved combination moistening and pressuring device adapted to deposit a uniform and balanced film of a fluid upon a base surface. Another object of the invention is to provide a moistening device adapted to dispense a readily volatile solvent which device is simple in construction and positive in operation. A further object of the invention is to provide a method and means for intermittently and controllably applying a uniform and balanced film of a fluid on a base surface. These and other objects of the invention will become apparent from the following description taken with the accompanying drawings in which:

Figure 1 is a vertical elevation partly in section diagrammatically illustrating details of the apparatus; and

Figure 2 is a fragmentary view partly in section taken along the line 2—2 in Figure 1.

Briefly, my invention contemplates an apparatus comprising a fluid reservoir, means for discharging fluid from said reservoir, a roller, means for mounting a roller adjacent the reservoir, and a spray tube means communicating with said discharge means and adapted to deposit a film of solvent fluid on the roller. This portable device is particularly adaptable for making transfers from small masters to any clear surface. Thus the device is designed for use where only one or a few copies of a multiplicity of small relatively rigid masters are to be made at relatively frequent intervals. Moreover, the apparatus is unique in its class, it being of such proportions that it is readily portable and can be used on odd shapes and on surfaces ordinarily inaccessible to prior art duplicating devices.

Referring to the drawings wherein like elements are identified by similar reference characters, the reservoir 10 comprises a chamber with means for positively engaging a valve chamber or roller support. Combined with these other elements, the reservoir 10 functions as the handle for the device and, if desired, it can be the original container for the fluid to be dispensed. A valve chamber 12 comprising for example a light casting of metal or plastic or the like, is fixed to the reservoir 10 and to the roller support member 13 by any suitable fluid-tight means including threads or off-set slots, and a washer

2

19 if necessary. This chamber 12 can be formed with a central hollow portion 15, a port or orifice 14, an inner threaded portion 17 adapted to engage the externally threaded portion 11 of the reservoir 10 and shoulder 16. The opposite end of the valve chamber 12 comprises a cylindrical recess 20 having internal threads 21 adapted to engage the roller support 13. The outer portion of the valve chamber 12 can be provided with a polygonal surface to facilitate its connection to the reservoir 10 and to the roller support 13.

A transverse cylindrical opening 22 is formed in the valve chamber 12, said opening extending 15 through one wall thereof across the axis of this portion of the valve chamber. Extending beyond the side wall of the valve chamber 12 is a hollow boss 23 in axial alignment with the opening 22, said boss 23 being internally threaded 20 ed. Within the opening 22 there is inserted a slide valve piston 24 carried by the piston rod or stem 26 which extends outside the valve chamber 12 and terminates in finger piece 27. The stem 26 of the plunger 24 extends through a packing gland 29 threaded into the boss 23. A quantity of packing 30 is placed around the stem 26 and is held in place by a packing nut 31, thus preventing leakage around the stem 26. An expansion spring 28 is interposed between the 30 packing gland 29 and the finger piece 27, said spring normally tending to actuate the valve piston or plunger 24 to its outer position.

Extending axially of the valve chamber 12 and through the bottom portion thereof is the internally threaded recess 20, the passageway 34 communicating at its upper end with a trough 35 in the wall of the valve opening 22. The lower portion of the passageway 34 extends downwardly through the body of the valve chamber 12 and terminates in the opening 36.

The roller support assembly 13 comprises a base portion including an externally threaded ring 42 and a top wall 43 having a central opening 45. A roller 40 is mounted for rotation on trunnions 47 in openings 48 in the arms 46 of the roller support member 13.

In connecting the roller and spray assembly 13 with the valve chamber 12 the threaded portion 42 engages the threads 21 in recess 20 and a ring washer 49 may be interposed between the upper face of the roller support 13 and the base 33 of the recess 20.

Adjacent the moistening roller 40, in spaced relation and parallel to the axis there is arranged a spray or distributing tube 50 having

a large number of fine holes or spraying nozzles 51 arranged along the length thereof in a single or in a plurality of rows. A conduit 52 passes through the opening 45 and connects the spray tube 50 to the valve chamber 12. One end of the conduit 52 can be flanged at 53 and recessed in 43 to complete a fluid-tight conduit from reservoir 10 to spray tube 50. If desired means can be provided on conduit 52 to prevent the turning of the conduit 52 and avoid any disalignment of the spray tube 50 with respect to the axis of the roller 40. In the illustrated embodiment, however, the ledges 57 are provided to align the tube 50 with the axis of the roller 40.

The moistening roller 40 and the spray tube 50 are illustrated as having an integral shield or cover 13 which protects the surface of the roller from interference and dust and minimizes evaporation of the fluid from the surface of the roller 40. Such a shield, however, may be omitted in some embodiments. If desired, however, a removable extension (not shown) of the shield 13 can be secured to the fixed shield 13 for completely enclosing the assembly during storage of the apparatus. The fixed shield may also support a capillary material which may be brought into contact with the roller 40 automatically or by the operator for further distributing the solvent sprayed on the cylindrical surface of the moistening roller and for absorbing any excess solvent.

The arrangement of elements enables the operator to moisten the roller 40 by depressing the finger piece 27 against the action of the spring 28. The solvent fluid trapped within the valve cylinder 22 is forced from the valve or pump chamber into the spraying or distributing tube 50 via trough 35, opening 34, and conduit 52, the fluid being distributed over the surface of the roller 40.

The construction described has the advantages that a predetermined amount of liquid will be positively delivered to the roller, and that the roller may be used either in the vertical or horizontal position and is not dependent upon capillary or gravity feed to the roller.

From the above description, it is apparent that I have attained the objects of my invention and have provided a moistening device wherein a uniform and positively controlled amount of solvent is applied to a clear surface in a simple and efficient manner. Furthermore, an improved portable moistening device of extremely simple operation and convenient proportions has been provided. It should be understood, however, that modifications may be made in the illustrated embodiments by those skilled in this art without departing from the spirit of the invention as defined by the appended claims.

What I claim is:

1. An apparatus comprising in combination an elongated liquid reservoir, a discharge opening in one end of said reservoir, a pump unit fixed to said reservoir adjacent said opening, a transverse cylindrical bore in said unit, a first inlet port in the wall of said bore and communicating with the opening in said reservoir, a piston slidable within said bore, a piston operating means extending exteriorly of said bore, a spring means acting on said operating means to urge said piston longitudinally within said bore to open said first port, a second outlet port in the wall of said cylin-

drical bore said second port discharging exterior of said bore and of said reservoir, a channel extending in the wall of said bore from said second port, a hooded support means carried by said pump unit, a roller mounted on trunnions within said hooded support means, said roller being disposed so as to expose a portion of said roller exteriorly of said hooded support, and a nozzle means within said hood and communicating with said second port, said nozzle means comprising a T-shaped tube, the discharge portion of which extends substantially the width of said roller and in juxtaposition to the cylindrical surface thereof.

15. 2. The duplicating device of claim 1 wherein the hooded support means is in threaded engagement with said pump unit, a gasket means is disposed between the hooded support and said pump unit, and the free ends of said T-shaped spray tube are aligned by the walls of said hooded support means.

3. An apparatus comprising in combination an elongated liquid reservoir, a discharge opening in one end of said reservoir, a piston pump unit 25 fixed to said reservoir adjacent said opening, a removable hooded support means threaded to said pump unit, a smooth-surfaced cylindrical roller mounted on trunnions within said hooded support means, said roller being disposed so as to be rotatable out of contact with said hood and to expose a portion of said roller exteriorly of said hooded support, and a nozzle means within said hood and communicating with said pump unit, said nozzle means comprising a T-shaped tube, a discharge portion of which extends substantially the length of said roller and in juxtaposition to but spaced from the cylindrical surface thereof.

4. An apparatus comprising in combination an elongated fluid reservoir means, a single port in one end of said reservoir means, a pump housing threaded to said reservoir about said port, a fluid pump means in said housing communicating with said port means, a hooded support means 40 removably attached to said pump housing, a cylindrical roller mounted within said support means with its cylindrical surface out of contact with said support and with a portion of the cylindrical surface rotatable outside the hooded support, said hooded support having a wide mouthed opening which is greater than the length of the roller in one dimension and greater than the diameter of the roller in another dimension, a perforated spray means in substantial coaxial alignment with said roller and disposed near but spaced from its cylindrical surface, and fluid-tight conduit means communicating with said fluid pump means and said spray means.
